UNITED STATES PATENT OFFICE.

WALTER ROMANOFF, OF PHILADELPHIA, PENNSYLVANIA.

DESIGN FOR AN ACCORDION CASE.

Application filed June 9, 1927. Serial No. 22,373. Term of patent 14 years.

To all whom it may concern:

Be it known that I, WALTER ROMANOFF, a citizen of Russia, residing at Philadelphia, county of Philadelphia, and State of Pennsylvania, have invented a new, original, and ornamental Design for Accordion Cases, of which the following is a specification, reference being had to the accompanying drawing, and forming part thereof.

The figure shows a perspective view of the accordion case, showing my new design.

I claim:

The ornamental design for an accordion case, as shown.

WALTER ROMANOFF.
